UNITED STATES PATENT OFFICE.

FRANZ TRINKS, OF BRUNSWICK, GERMANY.

ADDING-MACHINE.

1,400,106.

Specification of Letters Patent. Patented Dec. 13, 1921.

Application filed August 30, 1916. Serial No. 117,791.

(GRANTED UNDER THE PROVISIONS OF THE ACT OF MARCH 3, 1921, 41 STAT. L., 1313.)

To all whom it may concern:

Be it known that I, FRANZ TRINKS, citizen of the Duchy of Brunswick, Empire of Germany, residing at Brunswick, Germany, 5 have invented certain new and useful Improvements in Adding-Machines, of which the following is a specification.

The present invention relates to an adding machine, and more particularly to an 10 adding machine of the character in which the numbers and items are set up by means of keys and in which the numbers and items thus set up are transmitted to the accumulating mechanism through operation of the 15 main actuating member of the machine. In machines of this character it is usual to provide a printing mechanism in conjunction with the setting-up mechanism and the accumulator, for having the numbers and 20 items set-up, thereafter listed on a continuous sheet or strip of paper, the printing mechanism being likewise actuated through the main actuating member. In the machine to which the present invention more 25 particularly relates, there is also provided an indicating mechanism rendering the numbers and items set-up visible to the operator.

It is the object of the invention to generally improve upon adding machines of 30 this and similar character. A more specific object of the invention is to provide improved means for transmitting a total accumulated in the accumulating mechanism 35 into the printing mechanism to be set-up therein for listing at the conclusion of a computation or at any other time desired. It is a further object of the invention to provide means whereby a total transmitted 40 from the accumulator into the printing mechanism is rendered visible to the operator within the indicating mechanism. A still further object of the invention is to provide improved means whereby any total 45 which is being set-up in the indicating mechanism during the transmission of the total from the accumulator into the printing mechanism, may be restored in the accumulator by returning the indicating 50 wheels to zero.

These and other objects not specifically mentioned are attained by novel constructive and functional features in the mechanism embodying the invention and which

will now be described with reference to the 55 drawings the novel features being specifically set forth in the claims appended.

In the accompanying drawings, there has been illustrated an embodiment of the invention by way of example, it being understood that modifications within the scope of said invention may readily suggest themselves to those skilled in the art to which the present invention appertains. Figure 1 is a cross sectional side view of an adding 60 machine, showing one column of keys and the parts coöperating therewith. Fig. 2 is a view similar to Fig. 1, but showing parts not visible in the latter view. Fig. 3 is a detail view illustrating the coöperation of 65 the slidable actuating pins with the operating teeth in the revoluble setting-up disk. In Fig. 4 is shown a detail view of a portion of the zero restoring shaft for the accumulator. Figs. 5, 6 and 7, are detail views, 70 seen from the rear, of the printing type carrier; while Fig. 8 is a side view of the parts shown in Fig. 7 in a rear view.

Referring to the drawings, 1 designates a key board provided at the front of the 80 machine and containing keys 2 oscillatingly supported on small pivots 3. For each denominational order the illustrated machine contains a vertical column of keys 2 allotted to the numerals 1 to 9 as indicated in Fig. 1. 85 Each key stem 2 is provided at the front with a shoulder 4 bearing against the upper arm of a two-armed lever 5 which is fulcrumed at 6 and engages a slidable pin 8 with its lower extremity 5' (Figs. 1, 3). 90 Corresponding to the number of keys, there are provided nine pins 8 which are slidably mounted in a sector-shaped frame 8' (Fig. 3), and each pin 8 is under the action of a helical spring 7 which tends to retain the 95 pin in its inoperative position, shown in Figs. 1 and 3. To insure a parallel movement each pin 8 is provided with a lateral guide piece 10 fitted into guides in the frame 8'. On depressing any of the keys provided, the associated pin 8 is advanced into 100 operative position in which the same is retained by means of a spring-subjected and sector-shaped latching bar 56 (Figs. 1 and 3) that co-acts with the oblique face 85 of a laterally projecting shoulder 86 on each of said pins 8. When the latching bar 56 is again displaced subsequently by another

pin 8 of the same column of keys the previously advanced pin 8 will be permitted to return into its initial position while the pin last advanced is being retained by the latching bar in operative position. Thus, any error in depressing the wrong key will be simply rectified by depressing the proper key thereafter. To prevent two adjacent keys from being depressed at the same time, each key stem 2 is provided with an extension 9 which swings rearward and blocks the adjacent arm 5.

The inner ends of the pins 8 are provided with wedge-shaped operative faces 12 (see Fig. 3) which when the pin is in its advanced or operative position, project into the path of movement of teeth 14 mounted in an actuating disk 13. The teeth 14 project from the circumference of the actuating disk 13 and are oscillatingly supported on pivots 15 suitably secured within the actuating disk 13. Each tooth 14 is enabled to assume two extreme positions within an axially extending plane, as is indicated in Fig. 3. To secure each tooth 14 in either of its extreme positions, there is provided a locking pin 17 subjected to the action of a spring 16. The locking pin terminates in two wedge-shaped end faces adapted to co-act with similar end faces of the associated tooth 14. When an actuating pin 8 is being advanced into operative position, a number of the said teeth will strike the operative face 12 of the advanced pin 8 when the actuating disk 13 is revolved by means of the main operating member 18, and will in consequence be caused to swing into the other position, indicated in Fig. 3 in dotted lines. The number of actuating teeth thus rendered operative depends on the position of the pin 8 advanced by the associated key 2 and corresponds to the numeral the latter is representing. Depressing the lowermost key 2 representing the numeral 9 results in having the entire set of nine teeth provided within the actuating disk 13, swung into operative position for engaging a pinion 19 which is in mesh with the toothed wheel 20.

After having passed the pinion 19, the set of operative teeth 14 are brought into engagement with a second pinion 27 which is in mesh with the intermediate pinion 28, the latter engaging a pinion of the corresponding numeral wheel 29 included in the accumulating mechanism. For each denominational order there is provided such a numeral wheel 29 all of which are mounted on a transverse shaft 32 and below an observation aperture 30 through which the accumulated amounts become visible. At the conclusion of a computation it usually becomes desirable to extinguish or remove the accumulated total and to restore the numeral wheels 29 to their initial or zero position. The supporting shaft 32 is adapted to act

as a zero restoring shaft and for that purpose is provided with radially projecting pins 31, indicated in Fig. 4. The zero restoring shaft 32 is adapted to be displaced axially by a turning movement of the wing member 32. The shaft 32 is provided with a fixed stop 33 which when the shaft is being revolved, rides along a stationary cam 34 provided on the machine wall, thereby causing an axially directed displacement of the shaft 32 against the resistance of a helical spring 36 which is being tensioned. While the shaft 32 is thus axially displaced, the radial pins 31 are enabled to engage with studs 35 laterally projecting from each numeral disk 29, thereby causing the disk to partake of the revolving movement of the shaft 32 until reaching the initial or zero position. Toward the conclusion of a full turn of the zero restoring shaft 32, the helical spring 36 acts to axially move the shaft back into its inoperative position.

To effectively prevent the accumulating mechanism from accidentally moving beyond the determined positions, there is provided a latch 37 subject to the action of a spring 57 and having a locking tooth 38, designed to block the pinion 27 against rotation in the direction of the accumulating movement. The locking tooth is adapted to be lifted out of engagement with the pinion 27 by means of a cam 39 mounted on the actuating disk 13 to co-operate with an arm 40 of the latch 37 when the actuating disk 13 is being revolved. By means of the cam 39, the pinion 27 is released during the period of the accumulating operation and can then be engaged and turned by the operative teeth 14. When the last tooth 14 has passed the pinion 27, the cam 39 ceases to act upon the latch 37 which now follows the pressure of its spring 57 and reengages the pinion 27, thereby preventing the same from moving any further.

Prior to the conclusion of the movement of the main operating member 18, the operative teeth 14 strike a stationary wedge-shaped stop 41 disposed within the path of the movement of the teeth 14 and adapted to return them into their inoperative position.

The printing mechanism may be of any approved construction. In the drawings, I have shown a printing device which is more specifically described and claimed in my copending application Serial No. 112,574 and which I prefer to apply in conjunction with my present invention.

Each printing type carrying wheel 26 carries printing types on a portion of its circumference and gear teeth on another portion of its circumference. The toothed portion of the wheel 26 is in mesh with a toothed sector 24 which is secured to the corresponding wheel 20 and which causes the wheel 26 to partly revolve so as to bring

the numeral types running from 0 to 9 into printing position. In order to return to "0", the wheel will have to either complete the movement to a full revolution or to make 5 a return movement. The latter is the case in the illustrated example, in which the printing type carriers are advanced by the above mentioned toothed sectors 24 secured on the wheels 20, but are returned by a different device which will be described hereinafter.

The printing type representing the "0" is provided on a sliding block 42, see Figs. 7 and 8, which can be moved toward the circumference 15 of the wheel 26 or can be caused to recede toward the shaft 53 supporting the wheel 26. Normally the block 42 occupies the non-printing position, which is indicated in Figs. 1 and 8 in which no imprint 20 of the zero character will be produced when a sudden pressure is exerted upon the platen 43. However, when a numeral type is set up on any of the wheels 26, which involves that the wheel has been turned a corresponding amount, a lever 45 which normally projects into a notch 44 in the wheel, is depressed consequent upon the rotation of said wheel, this lever being in operative connection with a bridge piece 46 that transmits 25 the movement of the depressed lever 45 to the adjacent lever on the right. By means of similar bridge pieces all of the juxtaposed levers 45 are interlinked so that those succeeding each other on the right of the 30 one that is being depressed are forced, swing to their interconnection, to partake of the downward movement; see Fig. 5. An upwardly extending arm 45' on each of the levers 45 is provided with a terminal pin 45" 35 which engages a groove 42' in the associated sliding block 42 so as to cause the block to slide outward into printing position when the respective lever 45 is being depressed. When one lever 45 is being depressed those on the right are likewise depressed. The sliding blocks 42 controlled by the extensions 45' of the levers 45 depressed, move toward the platen 43 synchronously. Thus, when on any of the type 40 carriers 26 a numeral type is moved into printing position this will result in moving all those zero types into operative position which are situated on the right of the numeral type in printing position; while the zero types which are situated on the left remain in the non-operative position indicated in Figs. 1 and 8.

The return of the type carriers 26 is accomplished through the operation of the 45 main operating member 18 of the machine. For that purpose the shaft 47 carrying the disk 13 is provided with a geared portion 48 which drives the interconnected gear wheels 49, 50, 51 and 52 (Fig. 2), immediately on the performance of the printing

action. The gear wheel 52 is secured upon the zero restoring shaft 53 which is provided with studs 53' and a device for producing an axial movement of the said shaft comprising a stop 54, see Fig. 6, and an oblique cam face 54'. When the zero restoring shaft 53 is caused to revolve, the last mentioned device comes into action to axially displace the shaft thereby causing the studs 53' to engage lateral projections 55 on the type carrying wheels 26 and imparting to the latter the revolving movement whereby the same are returned to zero position.

When it is desired to print a total contained in the accumulator, a total transmitting mechanism is set into operation which will now be described.

Above the gear wheel 20 there is provided an oscillatory frame 63 (Fig. 1) supported 80 on pivots 64 on the machine casing. The frame 63 carries a transverse shaft 62 supporting for each denominational order a large gear wheel 21 engaging with the gear wheel 20, and in mesh with the first named 85 wheel a pinion 23 with an indicating disk 23' fixed thereto, on another transverse shaft 22. The indicating disk 23' is furnished with the numeral characters "0" to "9" but running in an opposite direction to the 90 equivalent numeral characters of the accumulator disks 29 above referred to. Through an observation aperture 23" the characters of the numeral disk 23' become 95 visible to the operator.

At the side of and in mesh with, the accumulator pinion 61 there is provided a pair of interengaging pinions 60, 59, (Fig. 1) with which the gear wheel 21 is designed to engage when for that purpose the frame 63 100 is swung toward the pinion 59. Means are provided for locking the said frame 63 in both of its extreme positions comprising a 105 slidably mounted locking pin 66 (Fig. 2) which is under the action of a helical spring 110 65 and is designed to engage slots 68 provided in a lateral extension 71 of the frame 63. For lifting the locking pin 66 out of the slots 68 there is provided a handle 67 fulcrumed at 64 and having a lateral arm 70 115 provided with cam faces 73, 73, adapted to engage a laterally projecting stud 69 on the locking pin 66 when the handle 67 is being moved by the operator. On advancing the handle 67 in the direction indicated by the 120 arrow in Fig. 2, the front cam face 73 lifts the locking pin 66 out of engagement with the respective slot 68 until the handle arm strikes the stop 72 provided on another extension of the frame 63, whereupon the 125 frame 63 is caused to move simultaneously with the said handle 67, until the extreme forward position of the frame 63 is reached whereupon the locking pin is allowed to engage the rearwardly positioned slot 68, thus 130

locking the said frame 63 in its forward position. When the handle 67 is being returned, the rearwardly positioned cam face 73 lifts the locking pin 66 in the initial part 5 of the movement of the handle 67, until the latter strikes the rearwardly positioned stop 72 whereupon the frame 63 is caused to partake of the return movement.

Since the accumulating mechanism is normally checked against movement by means of the latch 37, as hereinbefore described, means are provided for rendering said latch 37 inoperative when the accumulator is to be restored to zero through the action of the 10 wing member 32'; Fig. 4. These means are combined with the oscillatory frame 63, and set into operation simultaneously with the swinging of the frame 63. Rigidly connected with the frame 63 is a thrust bar 87 15 adapted to act upon an extension 88 of the latch 37. When the frame 63 is being swung toward the front by means of the handle 67, the thrust bar 87 depresses the extension 88 and thereby disengages the latch tooth 38 20 from the pinion 27. On the return of the frame 63, the latch 37 is automatically allowed to reengage the pinion 27.

When the gear wheel 21 is swung in mesh with the pinion 59, the total contained in the 25 accumulating mechanism is extinguished by a rotation of the wing member 32' on the shaft 32; see Fig. 4. This movement of rotation produces a setting-up of the total on the printing type carriers 26 through the 30 agency of the gear wheels 61, 60, 59, 21, 20, 24. If then the main operating member 18 of the machine is advanced without an actuation of any of the numeral keys, the sum previously totalized in the accumulating 35 mechanism will be caused thereby to be printed on the listing strip 58. It is one of the features of the present invention that the total contained in the accumulator is being set up on the indicating disks 23' at the same time 40 the total is extinguished by an operation of the zero restoring device of the accumulator. The total is visible through the observation apertures 23'' during the largest part of the 45 total printing operation, in fact as long as the printing mechanism is not being restored to zero. Through the return movement of the type carrying wheels 26 the toothed sector 24 and the gear wheels 20 and 21 are 50 caused to partake of the return movement 55 which is thus transmitted to the pinions 23 of the indicating mechanism which is thereby simultaneously restored to zero. Hence, no special zero restoring device is required 60 for the indicating disks 23'. If it is desired to restore the printed total in the accumulator, the frame 63 is left in its forward position with the wheel 21 in mesh with the pinion 59 when the printing device 65 is being returned to zero; then, the total previously printed will be retransmitted into

the accumulator while the indicating disks 23' are returned to zero position.

Although I prefer to have the gear wheel 21 continually in mesh with the gear wheel 20, this is not a requisite. The wheels 21 70 may be mounted to enable them to be displaced in axial direction after each transmission of a total from the accumulator to the printing device.

To produce the actual printing of the types moved into printing position, whether the same represent items or totals, there is provided an inking ribbon 74 which may be mounted, and moved past the printing position, in any well known manner. The listing strip 58 is mounted upon a roll 75 from which the same is drawn off and led past the printing position between pairs of guide rollers 76, 77, and 78, 79. The platen 43 is carried at the end of pivoted supports 80 and held out of contact with the ribbon 74 by a spring 80', see Fig. 2, while a lateral extension 80'' connects the suspenders 80 to a controlling lever 82 which is fulcrumed at 82' and projects into the path of movement of a cam disk 81 secured upon the shaft 53. When revolving, the cam disk 81 causes the platen 43 to strike against the types in printing position with the coloring ribbon 74 between platen and printing types; the item or total in printing position will thus be printed upon the listing sheet 58. At the conclusion of the revolution of the cam disk 81 the thrust bar 83 comes into action to advance the carrying wheel 84 of the lower guide roll 79 one step whereby the listing sheet is fed a corresponding amount and thereafter ready in position for another print.

What I claim as my invention and desire 105 to secure by Letters Patent of the United States, is:

1. In a machine of the character described, the combination of an accumulator comprising an accumulating pinion for each denominational order, a zero restoring device for said accumulating pinions, a printing mechanism, a total transmitting device between said accumulating pinions and said printing mechanism and adapted to operatively connect and disconnect said accumulating pinions with said printing mechanism, whereby a total contained in the accumulator may be transmitted into the printing mechanism on actuation of said zero restoring device, and an indicating disk for each denominational order in operative connection with said total transmitting device and having its indicating numerals arranged in an order opposite to that of the accumulating pinions so that on transmission of any total by restoring said accumulating pinions to zero the total transmitted is being set up on said indicating disks. 125

2. In a machine of the character described. 130

the combination of an accumulator, a zero restoring device for said accumulator, a printing mechanism, a total transmitting device between said accumulator and said printing mechanism and adapted to operatively connect and disconnect said accumulator with and from said printing mechanism, whereby a total contained in the accumulator may be transmitted into said printing mechanism by restoring said accumulator to zero, a pin for locking said total transmitting device both in its operative position and in its inoperative position, and a handle connected to shift said transmitting device from one of such positions to the other and provided with a pair of cams alternately engageable with said pin to lift the same out of locking position.

3. In a machine of the character described, the combination of an accumulating pinion for each denominational order, a zero restoring device for said accumulating pinions, a printing mechanism, a total transmitting device between said accumulating pinions and said printing mechanism and adapted to operatively connect and disconnect said accumulating pinions with said printing mechanism, whereby a total contained in the accumulating pinions may be transmitted to the printing mechanism on actuation of said zero restoring device, means for locking said total transmitting device in its operative and inoperative position, and an indicating disk for each denominational order in operative connection with said total transmitting device and having its indicating numerals arranged in an order opposite to that of the accumulating pinions, so that on transmission of any total from said accumulating pinions into said printing mechanism by restoring said pinions to zero the transmitted total is being set up on said indicating disks.

4. In a machine of the character described, the combination of an accumulating pinion for each denominational order, a zero restoring device for said accumulating pinions, a printing mechanism, an oscillatory frame, motion transmitting members on said frame for each denominational order and in operative connection with said printing mechanism, means for locking said oscillatory frame in either of its two positions, an oscillatory member adapted to render said locking means inoperative during the initial part of its oscillatory movement and to shift said oscillatory frame after having rendered said locking means inoperative, the shifting of said frame causing said motion transmitting members to operatively connect said accumulating pinions with said printing mechanism whereby on actuation of said zero restoring device any total contained in said accumulating pinions may be transmitted into said printing mechanism, and an indicating disk carried on said frame, in operative connection with each of said motion transmitting members, having its numerals arranged in an order opposite to that of said accumulating pinions so that on transmission of any total from said accumulating pinions into said printing mechanism by actuation of said zero restoring device the total transmitted is rendered visible on said indicating disks and may be restored in the accumulating pinions through return of said disks to zero.

In testimony whereof I have hereunto set my hand in presence of two subscribing witnesses.

FRANZ TRINKS.
